SECTIONAL REPAIR VULCANIZER FOR TIRES

Elby French, P.O. Box 111, Littleton, Colo.

Filed Apr. 11, 1960, Ser. No. 60,145

Term of patent 14 years

(Cl. D55—1)

FIG. 1 is a left perspective view of a sectional repair vulcanizer for tires showing my new design;

FIG. 2 is a right perspective view thereof; and

FIG. 3 is a front perspective view thereof.

I claim:

The ornamental design for a sectional repair vulcanizer for tires, as shown.
